UNITED STATES PATENT OFFICE.

HARRY J. PERKINS, OF GRAND RAPIDS, MICHIGAN.

GRINDING-MACHINE.

1,248,539.

Specification of Letters Patent.

Patented Dec. 4, 1917.

Application filed May 31, 1917. Serial No. 172,059.

To all whom it may concern:

Be it known that I, HARRY J. PERKINS, a citizen of the United States of America, residing at Grand Rapids, in the county of Kent and State of Michigan, have invented certain new and useful Improvements in Grinding-Machines; and I do hereby declare the following to be a full, clear, and exact description of the invention, such as 10 will enable others skilled in the art to which it appertains to make and use the same.

This invention relates to grinding machines adapted particularly for use in grinding cylindrical or tapered metal forms. It 15 is an object and purpose of the present invention to provide a grinding machine of very simple construction and operation whereby grinding of the work may be effected to a minute measure of accuracy. A 20 further object of the invention resides in the simplification of the construction shown in my former application for patent Ser. No. 118,019 filed Sept. 1, 1916, the present invention including various and novel features of construction and arrangements 25 whereby such simplification is attained and a machine produced at a much lower cost. Many other objects and purposes not particularly enumerated will appear and be 30 made clear as the description of the machine embodying my invention is understood, reference being had to the accompanying drawings in which;

Figure 1 is a front elevation of the machine.

Fig. 2 is a similar elevation with the front cover plate removed to show various parts of the driving and reversing mechanism.

Fig. 3 is a horizontal section taken sub- 40 stantially on the plane of line 3—3, Fig. 1.

Fig. 4 is an end elevation from the right of the machine shown in Fig. 1, parts being shown in section.

Fig. 5 is a vertical section substantially 45 on the plane of line 5—5 of Fig. 3.

Fig. 6 is a similar section on the plane of line 6—6, Fig. 1.

Fig. 7 is a side view, Fig. 8 a front elevation partially in section, and Fig. 9 is a 50 vertical section on the line 9—9 of Fig. 8, illustrating the controlling means for the cross feed of the grinder.

Fig. 10 is a section of a detail of structure relating to the automatic cross feed.

55 Fig. 11 is a front elevation; Fig. 12 is a central longitudinal section, and Fig. 13 a

transverse section of the combined reverse stop and tarry forming a part of my invention.

Fig. 14 is a longitudinal vertical section 60 of the mount for the grinding wheel shaft and

Fig. 15 is a diagrammatic plan view showing the layout of the principal elements of the machine and their operative relation to 65 each other.

In the several views of the drawings like reference characters refer to like parts, and the sectional views are all shown as looking in the direction indicated by the arrows. 70

In the construction of the machine a frame of cast iron, preferably, is provided, including a front wall 1 extending the entire length of the frame, a rear wall 2 of greater height than the front wall, ends 3 75 and 4 of substantially the same height as the rear wall 2 and connecting the ends of walls 1 and 2 together with an intermediate transverse wall 5 substantially half way between and paralleling the end walls 80 3 and 4. In addition transverse walls 6 and 7 extend to the rear from the wall 2 and are connected at their rear ends by a wall 8 paralleling the wall 2. Bases 9 and 10 extend to each side of the rearwardly projecting 85 portion of the frame formed by the walls 6, 7 and 8. Adjacent the end of base 9 a vertical support 11 is located, carrying a bearing 12 and a similar support provided with a bearing 13 extends from the base 10. A 90 shaft 14 is mounted in the bearing 12 on which, at one end, is fixed a combined clutch member and driving pulley 15. A movable clutch member 16 is associated with the member 15 and is splined on the end of a shaft 17 which extends through walls 6 and 7 and adjacent its opposite end is mounted in bearing 13. The movable clutch member 16 is adapted to be actuated in the usual manner by rocking a shaft 18 which extends 95 to adjacent the front of the machine, being carried at its front end in a bearing 19, and having a lever 20 at its front end by means of which it may be manually operated. Any suitable source of power may be used to 100 drive the member 15.

Between walls 6 and 7 the upper ends of walls 2 and 8 are formed with supporting members 21 and 22 on which a frame 23 is mounted, it in turn slidably supporting a 110 base 24. Spaced apart arms 25 are cast integral with the base and extend upwardly

and forwardly therefrom at their front ends being formed with bearings adapted to receive a shaft 26 to one end of which a grinding wheel 27 is secured. The grinding wheel 27 is partially covered in the usual manner by a hood 28 and the shaft carries a pulley 29 which is located between the two arms 25. Integral with the base 24 and disposed between arms 25 is a guard 30 which covers 10 and protects pulley 29 and the shaft on which it is mounted from water and dirt thrown off by the grinding wheel. Idle pulley 31 is mounted on the base 24 and 32 is mounted upon a member 33 back of the pulley 29. The member 33 is adjustably mounted on the base 24 between arms 25, a rod 34 connecting with the rear end thereof and passing through a stationary lug 35 with a strong compression spring 36 interposed between the lug and nuts on the rear end of the rod. The tendency of the spring is to move said member 33 and idle pulleys to the rear. An endless drive belt 37 passes over the idle pulleys around the pulley 29 25 and also around a drive pulley 38 fastened on the shaft 17, the grinding wheel being driven and the driving belt held under uniform tension in this manner.

A pulley 39 is also fixed to the end of 30 the shaft 17 adapted to drive a suitable pump 40 through a belt 41 as shown in Fig. 3. The pump is supported upon a tank 42 which in turn rests on the base 10 and has an intake pipe 43 extending into the tank. 35 The outlet pipe 44 extends upwardly and is turned over the hood 28 as indicated at 45 and then turned down and terminates in a nozzle 46 whereby the water is discharged directly onto the grinding wheel as shown.

40 Shaft 17 carries a worm 47 meshing with a worm wheel 48 on the rear end of a shaft 49 as shown in Fig. 4, the worm and worm wheel are housed by a casing 50. Shaft 49 extends forward through wall 2 and at a 45 point a short distance back and above the front wall 1 and has a beveled pinion 51 on its forward end which meshes with a similar pinion 52 splined upon a horizontal shaft 53 mounted in suitable bearings and 50 paralleling the front of the machine. A clutch member 54 is cast integral with the gear 52 with which a second clutch member 55 is adapted to engage the latter clutch member being cast integral with a collar 56 55 splined upon shaft 53. The movement of the collar and associated clutch member is controlled by a lever 57 which extends forward in front of the machine in position for ready manual operation.

60 At the end of the shaft 53 a series of gears 58 of different sizes are fixed which mesh with similar gears 59 and 60 mounted upon shaft 61 and 62, respectively. These gears are loose upon shafts 61 and 62 but are 65 adapted to be connected one at a time there-

to by the usual sliding key arrangements well known to all familiar with change speed transmissions of this type and I have indicated levers 63 and 64 at the front of the machine for controlling the keys, said 70 levers being mounted in operative relation to a selector arc 65 which indicates the gear selected. The specific method of operating the sliding keys is not shown as it forms no part of the present invention.

75 Shaft 62 at one end carries a gear 66 which is engaged with an idle pinion 67 it in turn meshing with a pinion 68 attached to a shaft 69 which is mounted at one end in the transverse wall 5 of the machine and 80 at the opposite end in a suitable bearing formed on a bracket 70 secured to and projecting from the frame of the machine. An elongated cylindrical roller 71 is fixed on shaft 69.

85 A table 72 is positioned directly above the supporting frame being slidably mounted on guides 73 and 74, the former of which is cast integral with the wall 2 while the latter is located horizontally at the front of 90 and between the end walls 3 and 4. A table 75 lies above the sliding table 72 and in practice is mounted upon a central vertical pivot (not shown) so as to swing thereon, such construction being described in my 95 previous application for patent. On the table 75, head and tail stocks 76 and 77 are secured in the usual manner, the former including a pulley 78 around which and the elongated roller 71 an endless belt 79 is 100 positioned whereby whenever roller 71 is driven the head stock is driven simultaneously therewith, the belt traversing the length of the roller 71 as the sliding table moves back and forth as hereafter described. 105 Between the centers of the head and tail stocks the work is held such as the cylinder 80 indicated in Fig. 15. It is, of course, understood that shaft 62 may be driven at a plurality of speeds with respect to the 110 shaft 53 due to the change speed gearing so that the proper speed of rotation of the work 80 may be secured.

115 In alignment with shaft 61 is a shaft 81 coupled thereto by a sleeve 82. Associated with shaft 81 as the usual reverse gearing 83 for grinding machines which, as it specifically forms no part of the present invention and is fully described in my previous application for patent above noted 120 is not here outlined. One element of the gearing comprises a bevel gear 84 secured at the front end of a shaft 85 on which, back of the gear, is a pinion 86 in engagement with a gear 87 fixed to a sleeve 88, which is 125 loose upon a shaft 89 above shaft 85. A pinion 90 is also connected with sleeve 88 and is in engagement with a rack secured lengthwise of and on the under side of the sliding table 72. By this arrangement with 130

the reverse movement imparted to shaft 85 the table 72 may be moved back and forth over the supporting frame. The usual lever for effecting the reverse movements of the 5 gearing and table is indicated at 92, having a projecting member 93 on its rear side against which heads 94 alternately engage for actuation of the lever. These heads are mounted upon a bar 95 secured to the front 10 of table 72 and are of special formation. Each includes a relatively stationary member 96 to the under side of which a second member 97 is secured, it extending a distance back of the member 96 and being 15 formed with notches 98 on its upper side to engage with the notches and the under side of the bar 95. It also includes an overhanging section 99 to receive the upper edge of the bar in which section a set screw 100 20 is located for the purpose of securing the device in any desired position along the length of bar 95. The member 96 is internally bored and is threaded at one end to receive an adjusting screw 101 by means of 25 which the finer adjustments for positioning the heads 94 may be effected. Each head 94 is integrally formed with a sleeve 102 inside of which a coil spring 103 under compression is placed, bearing against the end 30 of the screw 101 and surrounding a rod 104 fastened at one end to the head 94, extending lengthwise of the sleeve and passing loosely through the screw 101, receiving nuts 105 at its end whereby the adjustment 35 of sleeve 102 with respect to screw 101 is readily attained. The member 96 is split for a short distance adjacent the end which receives the screw 101 and a binding screw 106 passes therethrough serving to hold the 40 screw 101 in any position to which it may be adjusted.

This construction is of particular advantage as the sleeve 102 with attached head 94 may be spaced at its inner end a distance 45 from the screw 101 so that when the head 94 strikes the projection 93 on the reversing lever 92 a movement of the sleeve and compression of the spring 103 results, causing the sliding table and the work carried thereby to be carried a short distance 50 beyond the point that the reversal of movement would otherwise occur. The effect is to move the work at each end almost, if not quite beyond the grinding wheel to entirely 55 complete the grinding operation thereon before the return movement begins, having the same effect as a momentary stoppage of the table or tarry of the movement of the table between its opposite reverse movements.

The shaft 89 extends to a point in front of the machine and at its rear end carries a pinion 107 meshing with a gear 108 on the rear end of shaft 85. A hand wheel 109 65 is secured to the front end of the shaft

whereby, it will be observed, the sliding table 72 may be manually operated over the supporting frame to any desired point. In this connection it will be noted that the supporting frame 110 which carries bearing 70 for shaft 85, for the sleeve 88, and for the shaft 89 is detachably connected to the main frame of the machine and in practice is covered by a front plate 111 which is interposed between the upper edge of the front 75 wall 1 and the lower part of the guide 74, plate 111 being readily detachable for access to and removal of the entire mechanism just described if at any time it is desirable as for repairing. Likewise a supporting frame 80 work 112 carries the various gearings 58, 59, and 60 and the shafts associated therewith it also being back of the front plate 111 and readily removable if desired. It is for this reason that shafts 61 and 81 are separate and 85 connected together by the coupling 82.

A member 113 depends from base 24 in which is located a nut 114, shaft 115 threading therethrough and being mounted at its rear end in a bearing 116 in wall 8. At its 90 front end the shaft is squared extending through wall 2 and inserting into a socket in another shaft 117 mounted on the frame 110, at its front end carrying a gear 118 which meshes with a pinion 119 fixed on the 95 rear end of a sleeve 120 loose upon the shaft 89 which, at its front end in front of the machine, carries a hand wheel 121 by means of which it may be rotated in either direction to move the base 24 and the grinding 100 wheel carried thereby toward or away from the work. The detachable connection of shafts 115 and 117 permits the removal of the entire mechanism carried by the frame 110 as previously described. 105

The cross feed of the grinding wheel, operable manually by turning the hand wheel 121, may also be operated automatically if desired. Back of hand wheel 121 is a wheel 122 notched around its entire outer surface. 110 A member 123 is mounted loosely on sleeve 120 and at its upper end fashioned with a housing or shroud 124 which comes over wheel 122 and having mounted therein a small pinion 125 engaging with the notches 115 of the wheel and which may be manually operated by a head 126 located on the face of the member 123. A set screw 127 passing through the housing 124 and bearing against pinion 125 serves to lock the wheel and 120 member 123 together if desired. There is also attached to the housing a plate 128 lying adjacent to and conforming to the outer surface of wheel 122. A lever 129 at its upper end carries a pawl 130 adapted 125 to engage with the notches of wheel 122. The lower end of the lever is formed with an inclined face 131 against which one side of a spring pressed plug 132 engages. Said plug is mounted in a sleeve formed on the 130

end of a bar 133 pivotally mounted on the frame of the machine and lever 129 is pivotally mounted on an extension to said bar above the sleeve. The upper end of plug 132 has two angular faces, the face 131 of lever 129 engaging against one of them when it is in contact with the notched wheel and with the other when it is turned away from the wheel. A sleeve 134 connects with the 10 end of the bar 133 being positioned below it and having sliding engagement within a bracket 135 fixed to the main frame of the machine. A coil spring 136 normally elevates sleeve 134 and the bar 133 to which it is attached. A rod 137 is fixed to the sleeve 134 being positioned within the coil spring and at its end receiving nuts 138 whereby the position of the lever 129 with respect to the notched wheel may be adjusted. In 15 addition screws 139 thread upwardly through the bar 133 which is positioned immediately below an extension 140 to the reverse lever 92 and these screws may be adjusted and locked in the usual manner in 20 any desired position.

The mechanism described is operated by movements of the lever 92 as it is oscillated by the table 72. The movement of the lever 92 to either side of the vertical brings the 25 lower face of extension 140 against the end of a screw 139 thereby depressing the end of the bar 133 and the attached lever 129, whereby the member 130 rotates the wheel 124 a short distance and advances the grinding wheel correspondingly toward the work. The amount of the feed is regulated by the 30 adjustment of screws 139 and sleeve 134. Upon the return of the lever 92 to the vertical, spring 136 moves the lever 129 to its 35 original position the pawl 130 riding over the teeth of wheel 122. By connecting member 123 to wheel 122 the end of the plate 128 approaches closer and closer with each 40 successive feed to the member 130 or until 45 eventually it engages with and moves the pawl 130 away from the wheel 122 automatically stopping the cross feed; and it is apparent that the position of member 128 with respect to the wheel 122 may be set 50 so that the desired amount of material to be ground from the work is determined, the grinding stopping when the work has reached the desired size.

A grinding machine of the construction 55 outlined is of comparatively simple structure and by it all of the controls for the various movements of the mechanism are centralized in front of the machine. This machine is, as previously described, a simplification of the machine shown in my former application for patent and can be manufactured much more economically and is fully capable of handling work up to certain sizes. It is of course realized that 60 many changes in minor detail of construc-

tion may be resorted to without departing from the invention and accordingly I consider myself entitled to all such modifications which fall within the scope of the appended claims.

I claim:—

1. In a grinding machine, a sliding table, a support therefor, means to drive the table over the support, reversing mechanism for the table driving means and means mounted 75 on the table adapted to operate the reversing mechanism to change the direction of movement of the table, said means also operating to permit carrying the table a short distance beyond its normal stopping point 80 before beginning its reverse movement.

2. In a grinding machine, a support, a table slidably mounted thereon, stops adjustably mounted on and in front of the table, each including a relatively stationary 85 body, a member having a head mounted in the body, and a spring tending to move said head outwardly, means for driving the table over the support, reversing mechanism associated with the driving means and a 90 lever included in the reversing mechanism for operating the same, said lever extending upwardly between said heads, so as to strike thereagainst and compress the springs at 95 opposite extremes of movement of the table, substantially as described.

3. A combined reversing stop and tarry for grinding machines including a body interiorly bored and threaded at one end, means for attaching the body to the sliding 100 table of a grinding machine, a pin having a longitudinal opening therethrough secured into the threaded end of the body, a sleeve provided with an outer head slidably inserted in the opposite end of the body, a 105 rod attached to the head, passing lengthwise of the sleeve and through said threaded pin, nuts threaded on to the end of the rod, and a coiled spring within the sleeve interposed between the head and said threaded 110 pin.

4. In combination, a support, a table slidably mounted thereon, a driving shaft at the rear and lengthwise of the support, a shaft located adjacent the front and lengthwise of the machine, a transverse shaft, a worm gear at the rear end of the transverse shaft, a worm on the driving shaft meshing therewith, gearing connections between the front end of the transverse shaft and the second 115 shaft, means to drive the table back and forth over the support from said second shaft, head and tail stocks on the table, and means to drive the work held between said head and tail stocks from said second shaft, substantially as described.

5. In combination, a main support, a shaft mounted thereon, a table mounted to move lengthwise of the support, a second shaft, means to drive the same from the first shaft,

table driving mechanism including a table reverse mechanism driven by said second shaft, an auxiliary support for carrying the table driving and reverse mechanism detachably connected to the main support, a grinding wheel, a transversely adjustable base on which the wheel is mounted, mechanism to move the base transversely of the main support, from in front of the machine, said mechanism being partially carried by said auxiliary support, and part by the base and main support, and a freely detachable connection between said parts of the mechanism, permitting free removal of the auxiliary support, substantially as described.

6. In a grinding machine, a main support, a base mounted for movements transversely of the support, a grinding wheel mounted on the base, an extension to the base, a shaft 20 threaded through said extension and having a bearing in the rear portion of the main support, an auxiliary support detachably connected to the main support adjacent the front portion thereof, a shaft provided 25 with a socket therein mounted on the auxiliary support, said socket receiving the forward end of the first shaft, and means to rotate said second shaft, substantially as described.

30 7. In a grinding machine, a sliding table, a grinding wheel, means for driving the wheel, means for moving the table back and forth in front of the grinding wheels, including a reversing lever pivotally mounted 35 at the front of the machine, means on the table to tilt the lever at the end of each reciprocatory movement of the table, a shaft rotatably mounted transversely of the machine, a sleeve loosely mounted around the 40 shaft, a notched wheel on the end of the sleeve, means operated by rotation of the sleeve for moving the grinding wheel transversely of the machine, and extension to the reversing lever, a horizontal bar pivotally 45 mounted at one end below said extension, a vertical sleeve and a vertical extension formed at the free end of the bar, a lever pivotally mounted on said extension to said bar, a pointed dog secured in rigid relation 50 to the end of the lever, said dog engaging against the notched wheel, means carried by the sleeve and engaging with the lever to yieldingly force said dog against the notched wheel, a spring actuated plunger 55 attached to the sleeve and adjacent screws threading through said bar directly below and adapted to be associated with said extension to the reversing lever.

8. In combination, a main support, a table 60 slidably mounted thereon to move lengthwise of the support, work holding means mounted on the table, a single drive shaft for driving the table and the work holding means, gearing connections between said 65 shaft, said table and said work holding

means, and two separate auxiliary supports for carrying the same detachably connected to the main support, whereby either with the mechanism supported thereby may be removed at will from the main support.

9. In a grinding machine, a main support, a main driving shaft at the rear of the support, a worm thereon, a circular shaft adjacent the front of said support, a transverse shaft, a worm wheel at the rear end 70 thereof engaging with the worm, a combined beveled gear and clutch member loosely mounted on the circular shaft, a similar gear at the forward end of the transverse shaft meshing with said beveled gear, a clutch member splined on the circular shaft, means to move the same into and out of engagement with the first clutch member, a table mounted for movements lengthwise of the support, means interposed 75 between the counter shaft and table for operating the same back and forth over the support, work holding devices mounted on the table, and means to drive the same interposed between said counter shaft and said 80 work holding devices, substantially as described.

10. In a grinding machine, a support, a table mounted to move back and forth lengthwise of the support, an elongated 85 roller rotatably mounted on the support, a headstock carried by the table, a headstock center rotatably mounted on said headstock, including a pulley connected to said center, an endless belt passing around the roller 90 and pulley, a driven shaft, means to drive the same, a transmission gearing including a second shaft adapted to be driven by said driven shaft, a gear connected to the second shaft, a pinion on the roller, and gearing 95 connections between said gear and pinion.

11. In a grinding machine, a support, a table mounted to move back and forth lengthwise of the support, a headstock including a rotatably mounted headstock 100 center carried by the table, a shaft, means to drive said shaft, a rotatably mounted elongated roller mounted on the support, gearing connections between said shaft and roller for driving said roller directly from 105 the shaft, and belt connections between the roller and headstock center for driving said center from the roller.

12. In a grinding machine, a support, a base mounted to move transversely of the 110 support, a second shaft carried by said base, a grinding wheel on the shaft, a pulley on said second shaft, a drive pulley on the drive shaft, an idle pulley mounted on the 115 base, a member slidably mounted on the base, an idle pulley on said member back of the first idle pulley, a lug projecting upwardly from said member, a second lug similarly projecting from the base, a rod secured to the first lug extending loosely through 120 125 130

the second lug, a coiled spring under compression around the rod and disposed between the second lug and a head at the end of the rod, and a belt passing around the 5 pulleys on said shafts and over said idle pulleys.

13. In a grinding machine, a support, a table mounted for slidable movements back and forth over the support, an elongated 10 roller rotatably mounted on the support below the table, a headstock on the table, a rotatably mounted center mounted on the

headstock said center including a pulley adapted to receive a belt and located directly above the roller, a belt passing around the roller and pulley, a sleeve slidably mounted on the support back of the belt, a roller on the end of the sleeve, and a coiled spring under compression housed within the sleeve and disposed with its rear end bearing 15 against the support, substantially as described. 20

In testimony whereof I affix my signature.
HARRY J. PERKINS.
